UNITED STATES PATENT OFFICE.

GEORGE A. SHOEMAKER, OF CHICAGO, ILLINOIS, ASSIGNOR TO BAKER-VAWTER COMPANY, OF PORTLAND, MAINE, A CORPORATION.

BINDER-LOCK.

No. 853,879.

Specification of Letters Patent.

Patented May 14, 1907.

Application filed December 21, 1903. Serial No. 186,050.

To all whom it may concern:

Be it known that I, GEORGE A. SHOEMAKER, a citizen of the United States, residing at Chicago, in Cook county and State of Illinois, have invented a new and useful Improvement in Binder-Locks, of which the following is a full and accurate description, reference being had to the accompanying drawings.

10 My invention relates especially to that class of binders in which economy of construction is desired, and resides in the peculiar mechanism herein described by which simplicity, strength and economy of manufacture is secured.

15 In the drawings, Figure 1 represents in perspective a binder fitted with my lock. Fig. 2 is an enlarged view of a vertical section taken through the line 2—2 of Fig. 1.

20 Fig. 3 is a horizontal sectional view taken through the line 3—3 of Fig. 1. Fig. 4 is a detail drawing of the several parts of my locking mechanism.

25 More particularly, A and A' represent the binding bars of my binder.

B, B' represent the binding posts of my binder, which preferably consist of telescoping sections secured respectively to the bars A and A', but may be constructed of any desirable form or style or number. I prefer to construct them as follows: Projecting from the bar A' is a stud b. In opposition thereto, and having telescopic relation therewith, a tube b' projects from the bar A and is fitted 35 at its inner or free end with an inwardly turned rim or shoulder b². Fitted in the upper or free end of the stud b is a screw b³, the head of which is larger in diameter than the stud b, and is designed to engage with the 40 rim or shoulder b² as the sections b and b' are drawn apart, thereby operating as a stop to prevent the separation of the sections b and b'.

45 C C represent the locking posts of my binder, are identical in construction and may be one or more in number, as is desired. The construction of the locking post C may be described as follows: A tube c is permanently attached to the bar A', and projects toward 50 the bar A. Attached to the bar A and projecting inwardly in opposition to the tube c is another and smaller tube c' which is designed to telescope with said tube c. The inner or free end of the tube c' is beveled as

shown at c² in Fig. 4 for the purposes herein-after shown. Extending through the tube c' is a shaft c³ sufficiently smaller than the tube c' to allow a slight lateral movement of the shaft c³. This shaft is fitted at its lower end with a head c⁴ and at its upper end with threads c⁵. The head c⁴ lies outside of the beveled end of the tube c'; it is of the same shape and the same diameter as the outside surface of the tube c'. On one side it is beveled c⁶ to correspond with the beveled end c² of the tube c'. The upper end c⁵ of the shaft c³ projects through a suitable aperture in the bar A and is here threaded. It is at this end c⁵ engaged by a thumb nut c⁷ which is larger in diameter than the aperture in the bar A 70 through which the end c⁵ of the shaft projects. To prevent the thumb nut c⁷ from being removed from the end of the shaft c³ in operation, a small headed screw c⁸ is countersunk into the nut c⁷ and screwed into the end c⁵ of 75 the shaft c³.

The action of my locking post C in operation is as follows. The tubes c and c' lying in telescopic engagement with each other, and the nut c⁷ turned as near to the end c⁵ of 80 the shaft c³ as the screw c⁸ will allow, the head c⁴ lies in the same perpendicular plane as the tube c' and the tube c' and the head c⁴ will slide easily within the tube c. By tightening the nut c⁷ or turning it onto the shaft 85 c³, the bar A acts as a shoulder for the nut c⁷ and the shaft c³ is drawn upward through the tube c'. This operation causes the beveled face c⁶ of the head c⁴ to slide in a lateral movement along the beveled end c² of the tube c'. 90 This moves the head c⁴ out of the plane of the tube c' and impinges the head c⁴ against the inner face of the tube c, thereby locking the post by frictional contact. A reversal of the aforesaid action releases the lock.

95 Covers to the binder may be employed or not as is desired, and may be attached in any desirable manner.

While I have described in detail a particular construction of a binder embodying my invention, I do not wish to be confined in minor details to the particular construction described. My invention embodies the locking post alone, and any form of construction of the other parts of the binder may be employed.

100 What I claim as my invention is
105 In a binder, the combination with binding

bars, and binding posts, of a locking post consisting of telescoping sections attached respectively to said binding bars, a shaft extending through the length of the smaller of said sections, and projecting with a threaded end beyond the outer face of the binding bar to which said smaller section is attached, a thumb nut fitted to said threaded end, a head fitted to the inner end of said shaft and lying within the said larger section and in contact

with the inner end of said smaller section at which point of contact, the said smaller section and shaft head are beveled correspondingly, substantially as described, and for the purposes herein set forth.

GEORGE A. SHOEMAKER.
